(57) **CLAIM**

The ornamental design for the foam dispenser, as shown and described.

DESCRIPTION

FIG. 1 is a side elevation of the foam dispenser including the canister;

FIG. 2 is a top view of the foam dispenser;

FIG. 3 is a side view of the foam dispenser;

FIG. 4 is a front view of the foam dispenser;

FIG. 5 is a rear view of the foam dispenser; and,

FIG. 6 is a perspective view of the foam dispenser. The broken line showing of a canister is for illustrative purposes only and forms no part of the claimed design.
